VAULT VENTILATOR

Earle McKay Jones, Minneapolis, Minn., assignor to Protection Equipment Co., Inc., Minneapolis, Minn., a corporation of Minnesota

Application March 28, 1952, Serial No. 279,020

7 Claims. (Cl. 98—33)

This invention has relation to a vault ventilator, or device for ventilating enclosures such as bank vaults.

The present application is a continuation in part of my pending application Serial No. 26,955, for Vault Ventilator, filed May 14, 1948, now abandoned.

The object of the invention is to provide a vault ventilator wherein will be incorporated desirable, novel and improved features and characteristics of construction.

In the accompanying drawings forming a part of this specification,

Fig. 1 is a front elevational view, partially broken away, of a vault ventilator made according to the invention;

Fig. 2 is a vertical sectional view, on a reduced scale, partially in elevation and partially broken away, of the vault ventilator disclosed in Fig. 1;

Fig. 3 is a horizontal sectional view, taken substantially as on line 3—3 in Fig. 2;

Figs. 4 and 5 are detail sectional views, taken substantially as on line 5—5 in Fig. 3, Fig. 4 showing a rotor of the vault ventilator situated as when sealing a vault closed, and Figs. 3 and 5 showing said rotor situated as when providing passageways for air to and from a vault;

Fig. 6 is an enlarged sectional view, taken on line 6—6 in Fig. 1;

Fig. 7 is a sectional view, agreeing generally with the disclosure of Fig. 3, detailing mechanism of modified construction for biasing a rotor of a vault ventilator incorporating features and characteristics of the invention toward a position thereby providing passageways for air to and from a vault; and

Fig. 8 is a detail sectional view, taken as on line 8—8 in Fig. 7.

The vault ventilator herein illustrated and described when applied to use will be located in an exterior wall of an enclosure to be ventilated, such, for example, as a bank vault. In the disclosed embodiment of the invention, an exterior wall of a vault to be ventilated is constituted as concrete 10 having its inner and outer surfaces covered by slabs, denoted 11 and 12, respectively, which may be of any material suitable to their purpose.

First and second housings, represented 13 and 14, respectively, of the vault ventilator are suitably and conveniently imbedded in the concrete 10 in spaced apart, horizontally aligned relation to each other. The first housing 13 is imbedded in an interior part of said concrete 10 with its interior end portion situated in an opening through the inner slab 11, and the second housing 14 is imbedded in an exterior part of the concrete 10 with its exterior end portion situated in an opening through the outer slab 12.

The first housing 13 is constituted as spaced apart, oppositely disposed, complementary, vertical members, represented 15 and 16, respectively, suitably and conveniently supported, as at 17, in the concrete 10, and a part-cylindrical member 18, between exterior end portions of the vertical members 15 and 16, suitably and conveniently supported, as at 19, in said concrete. Said first

2

housing 13 is open at its interior end and is closed at its exterior end by the part-cylindrical member 18 and reduced curvilinear portions, indicated 20 and 21, respectively, on the vertical members 15 and 16. Openings, designated 22 and 23, respectively, through the exterior end portion of the first housing 13 lie in a horizontal plane at opposite ends of the part-cylindrical member 18. An annular guideway 24 provided by and at the interior side of the part-cylindrical member 18 is for a purpose to be set forth.

The second housing 14 is of rectilinear configuration. It is defined at its top and bottom by upper and lower walls, denoted 25 and 26, respectively, at its opposite sides by walls 27, 27, and at its interior end by a transverse wall 28 disposed in parallel relation to the inner and outer slabs 11 and 12. Openings, indicated 29 and 30, respectively, through the transverse wall 28 are in aligned relation with the openings 22 and 23, respectively, in direction widthwise of the vault wall. The second housing 14 can be imbedded in said vault wall in suitable and convenient manner, and the exterior side of said second housing, contiguous with the exterior side of the vault wall, is open.

Although the exterior end of the first housing 13 could be in proximate relation to the transverse wall 28 defining the interior end of the second housing 14, in the disclosure as made tubular connections, represented 31 and 32, respectively, extend between the openings in the end of said first housing and the openings in said transverse wall 28 to provide air conveying passageways contiguous at their opposite ends with the first and second housings, respectively. The tubular connections 31 and 32 can be assembled with the first and second housings in any suitable and convenient manner.

A closure door for the exterior side of the second housing 14, at the exterior side of the vault wall, is represented 33. A lower part of the closure door is hinged, as at 34, upon an exterior part of the lower wall 26 of said second housing, and an upper part of said closure door includes a latch 35 adapted to be engaged back of a keeper 36 supported at an upper part of the second housing. A knob for manipulating the latch 35, situated at the exterior side of the closure door 33, is denoted 37. The construction and arrangement will be such that when said closure door is in closed position, it will be situated within the confines of the second housing 14.

An electric motor 38 and a blower 39, constituted as a unitary structure, are rigidly supported, as indicated generally at 40, upon the closure door 33 to be situated within the second housing 14 when said closure door is in closed position, and outside of said second housing when the closure door is open.

The blower 39 is situated in spaced relation to one of the side walls 27 of the second housing 14 when the closure door 33 is in closed position, and an inlet for air to said blower is by way of an opening 41 through said closure door and a channel 42 provided by a U-member 43 rigid with the blower. The opening 41 is overhung by a hood 44 upon the exterior surface of the closure door.

The electric motor 38 is situated in spaced relation to the side wall 27 of said second housing 14 spaced from the blower 39 when said closure door 33 is in closed position, and an outlet for air from the second housing is by way of an opening 45 through the closure door. The opening 45 is overhung by a hood 46 upon the exterior surface of said closure door.

An outlet passageway from the blower 39, adapted to lead to the tubular connection 31, is provided by a conveying connection 47 leading from said blower. The construction and arrangement will be such that an interior end of the conveying connection 47 will be fitted

up against the transverse wall 28 of the second housing 14, as in Figs. 2 and 3 of the drawings, when the closure door 33 is in closed position, in surrounding relation to the opening 29 through said transverse wall, and also such that said conveying connection 47 will be removed from engaged relation with the transverse wall when the closure door is opened. The tubular connection 32 is at the side of the blower 39 adjacent the electric motor 38, the opening 30 through the transverse wall 28 is contiguous with the interior side of a chamber of the second housing 14 containing said electric motor, and the opening 45 through the closure door 33 is contiguous with the exterior side of said chamber of said second housing containing the electric motor.

A rotor 48 of the vault ventilator, situated within the first housing 13, is mounted on a horizontal axis and is of cylindrical configuration. Parallel, opposite end walls, indicated 49 and 50, respectively, of said rotor are situated adjacent and rotatably supported upon the housing members 15 and 16. Pivotal supports, designated 51 and 52, respectively, constituted as threaded elements in the disclosure as made, are rigidly mounted in and extend inwardly from said housing members 15 and 16, and inner end portions of said pivotal supports provide trunnions, in alined relation to each other at the longitudinal axis of the rotor 48, situated in depressions in said opposite end walls 49 and 50 and rotatably supporting said rotor. The rotor is of such diameter that one side thereof will lie in adjacent relation to the interior ends of the tubular connections 31 and 32 while the opposite side thereof lies in adjacent, accessible relation to the open, interior end of the first housing 13.

Transversely extending passageways, represented 53 and 54, respectively, through the rotor lie in a single plane and are adapted to be alined with passageways through the tubular connections 31 and 32, respectively, as in Figs. 2, 3 and 5 of the drawings, or to be situated at right angular relation to said tubular connections, as in Fig. 4. When the passageways 53, 31 and 54, 32 are alined and the electric motor 38 is in operation, air will be drawn from outside atmosphere into the vault through the opening 41, the channel 42, the blower 39 and its conveying connection 47, the tubular connection 31 and the passageway 53 and expelled from said vault to outside atmosphere through the passageway 54, the tubular connection 32, the chamber of the second housing 14 having the electric motor 38 and the opening 45. When said passageways 53, 31 and 54, 32 are out of alinement, the rotor 48 will effectively shut off the interior of the vault from the exterior thereof. The passageway 53 is in an end portion of the rotor 48 adjacent the housing member 15, and the passageway 54 is in an end portion of said rotor adjacent the housing member 16.

An actuator for the rotor 48 consists of an annular flange 55 disposed in perpendicular relation to said rotor at its midlength, between the transverse passageways 53 and 54. An exterior portion of said actuator or annular flange 55 is rotatable in the annular guideway 24 which the part-cylindrical member 18 provides, and said part-cylindrical member terminates at its interior side in spaced relation to innermost parts of the rotor 48 and the actuator or annular flange 55. The construction and arrangement will be such that said actuator or annular flange 55 is freely accessible at the interior side of the vault wall. The part-cylindrical member 18 desirably can include a protuberance 56, within the annular guideway 24, providing a surface 57 adapted to be engaged by a shoulder 58 on the actuator or annular flange 55 to limit the extent to which the rotor 48 can be rotated in clockwise direction and a surface 59 adapted to be engaged by a shoulder 60 on said actuator or annular flange to limit the extent to which said rotor can be rotated in counterclockwise direction. The rotor 48 is hollowed out, as indicated at 61, 61, at locations above the transverse passageways 53 and 54 in Figs. 2, 3 and 5, and to the right of said trans-

verse passageways in Fig. 4, so that the left side of said rotor as shown in said Fig. 4 is much heavier than the right side and the rotor is effectively counterweighted to rotate in counterclockwise direction when released from its position as in Fig. 4, where the transverse passageways 53 and 54 are at right angular relation to the tubular connections 31 and 32, to its position as in Figs. 2, 3 and 5, where said transverse passageways are alined with said tubular connections 31 and 32 and the shoulder 60 is engaged against the surface 59 thus to retain the rotor in position to complete the air circulatory system through the vault wall which the vault ventilator has been devised to provide.

Mechanism for retaining the rotor 48 in position to shut off the interior of the vault wall from the exterior thereof, as in Fig. 4, is very clearly disclosed in Figs. 1 to 6.

A panel upon a lower portion of the inner slab 11 is denoted 62, and a cover upon said panel is indicated 63.

An electric switch 64 is suitably and conveniently supported upon the panel 62 beneath the cover 63.

Vertically alined, upper and lower bracket members, denoted 65 and 66, fixedly support horizontally spaced, vertical coils, indicated 67, 67, situated between said upper and lower bracket members. Vertical armatures, each indicated 68, are slidable in the coils 67, and a cross-head 69 extends between upper ends of the vertical armatures 68 and is rigidly secured thereto.

A vertical latching element 70, constituted as an elongated rod or bar, has an intermediate portion thereof slidably mounted, as at 71, in the upper bracket member 65, a lower end portion thereof slidably mounted, as at 72, in a vertical tube 73 rigid with the lower bracket member 66, and an upper end portion thereof fixedly secured, as by a set screw 74, in a portion of the cross-head 69 between and equidistantly spaced from the vertical armatures 68. An enlarged portion of the vertical latching element 70, between the upper bracket member 65 and the vertical tube 73, is denoted 75, and a compression coil spring 76, on the vertical latching element 70 between said enlarged portion 75 and the vertical tube 73, normally urges said vertical latching element in direction toward the actuator or annular flange 55, and also urges the vertical armatures 68 in direction away from the vertical coils 67.

The upper end of the vertical latching element 70 provides a shoulder 77 adapted to lie in a notch 78 in the actuator or annular flange 55 adjacent the shoulder 60 thus to retain the rotor 48 in the position in which disclosed in Fig. 4, and the enlarged portion 75 of the vertical latching element 70 is adapted to be moved away from the rotor 48 to cause the shoulder 77 to be released from the notch 78 when this is intentional.

Said enlarged portion 75 includes a V-slot 79 providing a camming surface 80 to be engaged by a camming surface 81 upon a working element of a push rod slidably mounted in the cover 63 and rigidly supporting a push button 82 situated at the inner side of said cover. A compression coil spring 83 upon the push rod normally urges the camming surface 81 in direction away from the camming surface 80.

A first battery for energizing the coils 67 is denoted 84, and a second battery for energizing the electric motor 38 is indicated 85.

A lead wire 86 interconnects the coils 67, a lead wire 87 extends from one of said coils 67 to the first battery 84, a lead wire 88 extends from said first battery to a normally open hand switch 89, and a lead wire 90 connects said hand switch with the other of the coils 67.

A lead wire 91 extends from the switch 64 to the second battery 85, a lead wire 92 extends from said second battery to the electric motor 38, and a lead wire 93 connects said electric motor with said switch 64.

A push button 94 of the switch 64 normally is in the open position of said switch, and an actuator arm 95 for moving the push button 94 to the closed position of the

switch 64 is engaged by an extension 96 upon and rigid with the cross-head 69.

Normally, the rotor 48 will be situated as in Fig. 4 of the drawings, with the shoulder 77 on the upper end of the vertical latching element 70 retained in the notch 78 in the actuator or annular flange 55 by reason of resilient action of the compression coil spring 76. When it is desired that said rotor be situated as in Figs. 2, 3 and 5, either the push button 82 or the push button of the normally open hand switch 89 will be actuated to cause said shoulder 77 to be removed from said notch 78. With release of the shoulder from the notch, the rotor 48 will rotate by gravity to aline the passageways 53 and 54 with the passageways through the connections 31 and 32, respectively.

The shoulder 77 will become removed from the notch 78 in response to depression of the enlarged portion 75 by actuation of the push button 82, and with removal of said shoulder from said notch, and rotation of the actuator or annular flange 55 in counterclockwise direction, the upper end of the vertical latching element 70 will, when said vertical actuator element is released, become engaged against the periphery of said actuator or annular flange, by reason of resilient force exerted by the compression coil spring 76. When the upper end of said vertical latching element is engaged against the periphery of the actuator or annular flange 55, the actuator arm 95 will be sufficiently depressed to cause the push button 94 to be held in the closed position of the switch 64. Stated otherwise, when the rotor 48 is in the position in which disclosed in Figs. 2, 3 and 5, the switch 64 is retained in the closed condition of the circuit for the electric motor 38 by reason of pressure exerted by the extension piece 96 upon the actuator arm 95 causing the push button 94 to be depressed.

Also, the shoulder 77 will become removed from the notch 78 in response to energization of the coils 67 by reason of manual closing of the normally open hand switch 89, with the ensuing results as set forth in the preceding paragraph. Whereas the push button 82 is disclosed as when situated within a vault to be ventilated, the normally open hand switch 89 can be situated in remote relation to the vault ventilator. For example, the hand switch 89 could be accessible in a vault other than one having the ventilator with push button such as 82 but capable of receiving atmospheric air from the vault having said ventilator. Or, circuits for the coils 67 could each include a hand switch such as 89 accessible at any locations which may be selected.

The rotor 48 is adapted to be rotated in clockwise direction from its position as in Figs. 2, 3 and 5 back to its position as in Fig. 4, and manual turning of said rotor can be accomplished by grasping a portion of the actuator or annular flange 55 at the interior side of the vault wall. With manual rotation of the rotor to position where the shoulder 77 is alined with the notch 78, said shoulder will be urged into said notch by the compression coil spring 76, and upon release of said rotor, while the shoulder is in the notch, the rotor will be retained in its position as in said Fig. 4. When said shoulder 77 is in said notch 78, the cross-head 69 will be elevated to extent permitting or causing the push button 94 to be in the open condition of the switch 64. That is, when the rotor 48 is in the position in which disclosed in Fig. 4, the switch 64 is retained in the open condition of the circuit for the electric motor 38.

It will be apparent that the electric motor 38 will be operative to drive the blower 39 at all times when the rotor 48 is situated as in Figs. 2, 3 and 5, and said electric motor will be inoperative to drive said blower when said rotor is positioned as in Fig. 4.

The closure door 33 is hingedly supported so that it can be swung to open position when it may be desired to pass articles, such, for example, as articles of food, through the vault wall by way of the passageways and

tubular connections 53, 31 and 54, 32 while these are alined. The construction and arrangement will be such that the circuit for the electric motor 38 will be broken when the closure door 33 is open and said electric motor and the blower 39 are situated exteriorly of the second housing 14.

In Figs. 7 and 8 there is disclosed mechanism of modified construction for rotating a rotor such as 48 from position as in Fig. 4 to position as in Figs. 2, 3 and 5.

A rotor 98, equivalent to the rotor 48 and similarly rotatably supported, is resiliently biased toward rotation in counterclockwise direction by an ordinary clock spring 99 having one of its ends 100 secured to a pivotal support for the rotor 98 and its other end 101 secured to an end of said rotor.

When the rotor 98 is released from position where held, as by a shoulder such as 77 in a notch such as 78, with its transverse passageways, equivalent to the transverse passageways 53, 54, out of alinement with tubular connections such as 31, 32, the clock spring 99 will urge said rotor to its position as in Fig. 8, where a shoulder 102, equivalent to the shoulder 60, of the rotor, is engaged against a surface 103, equivalent to the surface 59, of a protuberance 104, equivalent to the protuberance 56.

The clock spring 99 performs the same function as is performed by reason of counterweighting the rotor 48, and, otherwise than as described, a vault ventilator as in Figs. 7 and 8 can be of the same construction as is a vault ventilator made according to the disclosure of Figs. 1 to 6.

What is claimed is:

1. In a vault ventilator, a housing having an open side and a curved side embedded in a wall, there being a continuous opening through the curved side of said housing and said wall, a rotor constituted as a cylindrical member in and extending transversely of said continuous opening and having its longitudinal axis mounted in the housing and its periphery disposed in adjacent relation to the curved side of said housing, said cylindrical member having a transverse passageway therethrough to be out of alinement with said continuous opening when the rotor is in a first position closing off the continuous opening and to be alined with said continuous opening when said rotor is in a second position, means biasing said rotor normally to situate it in said second position, means accessible at an inner side of said wall for rotating the rotor about its longitudinal axis from said second position to said first position, first mechanism for retaining said rotor in said first position against force of said biasing means, and second mechanism for releasing the rotor when in said first position to action of said biasing means.

2. The combination as specified in claim 1 wherein said biasing means comprises a counterweight on said rotor.

3. The combination as specified in claim 1 wherein said biasing means is composed of resilient material.

4. The combination as specified in claim 1 wherein said first mechanism is constituted as a latching element for engaging a notch in said rotor and said second mechanism is constituted as a solenoid for moving said latching element away from said rotor and a circuit for said solenoid.

5. A vault ventilator comprising a housing having an open side and a curved side embedded in an inner side of a wall, there being a continuous opening through the curved side of said housing and said wall, a rotor constituted as a cylindrical member in and extending transversely of said continuous opening and having its longitudinal axis mounted in the housing and its periphery disposed in adjacent relation to the curved side of said housing, said cylindrical member having a transverse passageway therethrough to be out of alinement with said continuous opening when the rotor is in a first position closing off the continuous opening and to be alined with said continuous opening when said rotor is in a second position, means biasing said rotor normally to situate it in

said second position, means accessible at an inner side of said wall for rotating the rotor about its longitudinal axis from said second position to said first position, latching means for retaining said rotor in said second position, mechanism for releasing the rotor from said latching means to action of said biasing means, there being a compartment in an outer side of said wall, a blower in said compartment having a conveying connection communicating with an end of said continuous opening bounded by said wall and in spaced relation to said rotor, an electric motor in said compartment for actuating said blower, and a circuit for said motor.

6. A vault ventilator comprising a housing having an open side and a curved side embedded in a wall, there being a continuous opening through the curved side of said housing and said wall, a rotor constituted as a cylindrical member in and extending transversely of said continuous opening and having its longitudinal axis mounted in the housing and its periphery disposed in adjacent relation to the curved side of said housing, said cylindrical member having a transverse passageway therethrough to be out of alinement with said continuous opening when the rotor is in a first position closing off the continuous opening and to be alined with said continuous opening when said rotor is in a second position, means biasing said rotor normally to situate it in said second position, means accessible at an inner side of said wall for rotating the rotor about its longitudinal axis from said second position to said first position, first mechanism for retaining said rotor in said first position against force of said biasing means, second mechanism for releasing the rotor when in said first position to action of said biasing means, a blower having a conveying connection communicating with an end of said continuous opening bounded by said wall and in spaced relation to said rotor, an electric motor for actuating said blower, a circuit for said motor, and means controlled by said first mechanism operative to retain said circuit in open condition while the first mechanism is operative to retain said rotor in said first position and in closed condition while said biasing means is operative to retain the rotor in said second position.

7. A vault ventilator comprising a housing having an open side and a curved side embedded in a wall, there being a continuous opening through the curved side of said housing and said wall, a rotor constituted as a cylindrical member in and extending transversely of said con-

tinuous opening and having its longitudinal axis mounted in the housing and its periphery disposed in adjacent relation to the curved side of said housing, said cylindrical member having a transverse passageway therethrough to be out of alinement with said continuous opening when the rotor is in a first position closing off the continuous opening and to be alined with said continuous opening when said rotor is in a second position, means biasing said rotor normally to situate it in said second position, means accessible at an inner side of said wall for rotating the rotor about its longitudinal axis from said second position to said first position, a latching element for engaging a notch in a peripheral surface of said rotor to retain it in said first position against force of said biasing means, resilient means urging said latching element toward and against said peripheral surface, a solenoid for moving said latching element away from said rotor to release the rotor when in said first position to action of said biasing means, manually operable means for moving said latching element to release said rotor when in said first position to action of the biasing means, a blower having a conveying connection communicating with an end of said continuous opening bounded by said wall and in spaced relation to said rotor, an electric motor for actuating said blower, a circuit for said motor, and means controlled by said latching element operative to retain said circuit in open condition while the latching element is operative to retain the rotor in said first position and in closed condition while said biasing means is operative to retain the rotor in said second position.
